UNITED STATES PATENT OFFICE

118,576

DESIGN FOR A SHOE

William H. Thompson, Brookline, Mass., assignor to French, Shriner & Urner Manufacturing Co.,
Boston, Mass., a corporation of Massachusetts

Application October 24, 1939, Serial No. 87,833

Term of patent 3½ years

To all whom it may concern:

Be it known that I, William H. Thompson, a citizen of the United States, residing at Brookline, in the county of Norfolk and State of Massachusetts, have invented a new, original, and ornamental Design for a Shoe, of which the following is a specification, reference being had to the accompanying drawing, forming part thereof.

In the drawing,

Fig. 1 is a top perspective view of a shoe, showing my new design; and

Fig. 2 is a side elevation looking toward the opposite side of the shoe as shown in Fig. 1.

I claim:

The ornamental design for a shoe, substantially as shown.

WILLIAM H. THOMPSON.
